UNITED STATES PATENT OFFICE.

WILLIAM I. BUNKER, OF LA GRANGE, ILLINOIS.

DESIGN FOR A BICYCLE-SADDLE.

SPECIFICATION forming part of Design No. 24,878, dated November 12, 1895.

Application filed October 11, 1895. Serial No. 565,423. Term of patent 7 years.

To all whom it may concern:

Be it known that I, WILLIAM I. BUNKER, a citizen of the United States, residing at La Grange, Cook county, Illinois, have invented and produced a new and original Design for Bicycle-Saddles, of which the following is a specification, reference being had to the accompanying drawings, forming a part hereof.

In the accompanying drawings, Figure 1 o represents a plan view of my design, looking at it from the top; and Fig. 2, a transverse section taken on the line 2 of Fig. 1.

The leading feature of my design consists in the body portion for a saddle formed of two semielliptical portions joined together at their ends and provided with two inner in-

dentations, so as to resemble when viewed in plan view, as shown in Fig. 1 of the drawings, an outline representing the letter O.

A A' are the body portions of the saddle, joined together near their ends at a and provided with interior projections a'.

In the sectional view, B is the supporting-frame, b the sustaining-socket, and b' a securing set-screw.

What I claim is—

The design for a bicycle saddle herein shown and described.

WILLIAM I. BUNKER.
